UNITED STATES PATENT OFFICE

HAROLD L. NASH, OF SOUTH NORWALK, CONNECTICUT, ASSIGNOR TO NASH ENGINEERING COMPANY, OF SOUTH NORWALK, CONNECTICUT, A CORPORATION OF CONNECTICUT

COMPRESSOR

Application filed October 19, 1929. Serial No. 400,900.

This invention relates to air compressors or pumps of the rotary liquid-piston type and particularly to pumps or compressors of this type which employ a rotor in combination 5 with an endless revolving liquid body or ring, the orbit of which is controlled by the eccentric shape of the compressor casing in such a manner as to effect the compression of the air.

10 It is an object of this invention to provide a compressor of this general type which embodies means for increasing the final discharge pressure of the air by subjecting it to the influence of a supply of high pressure 15 water or other liquid in addition to the compressive force of the liquid piston.

A further object is to provide a unitary device of this class which includes in combination an air compressor of the type described, 20 and a liquid pump for providing the liquid under pressure for accomplishing the further compression of the air.

In the attainment of these objects, this invention contemplates the provision of a rotor 25 which is provided with the usual shrouds at its sides connected by a series of vanes between which are formed displacement chambers or buckets. This rotor is arranged to revolve in a casing of generally elliptical or 30 oval shape providing eccentric portions or lobes of substantially crescent shape at intervals around its periphery. The casing and the rotor buckets are provided with ports which register at certain points during the 35 rotation for the admission and exhaust of air. As the rotor is driven at high speed the vanes impart a rotary motion to the liquid which partly fills the casing and, due to the centrifugal force developed, this liquid 40 assumes a ring shape and will alternately partially recede from the chambers or buckets of the rotor and return therein, as it is guided in its eccentric orbit around the interior of the casing. As this revolving body of liquid 45 recedes from the buckets upon reaching a lobe portion of the casing, it draws air into the inner portion of the buckets near the hub of the rotor through the registering openings or ports in the bucket and casing walls, and as 50 the outer wall of the casing again curves in

toward the periphery of the rotor, the ports no longer register and the liquid ring upon again nearing the center of the rotor compresses the air in the buckets until it is expelled upon registry of the bucket ports 55 with the outlet ports of the casing. Between the points of greatest compression of the air during the movement of the rotor, (that is, the point where the casing approaches closest to the periphery of the rotor), and the point 60 where the bucket ports register with the outlet port, the outer wall of the casing is cut away to provide an admission port of relatively large area for the high pressure fluid. Beyond this port the outer wall of the casing 65 again converges from a spaced position with relation to the rotor periphery to a position nearly in contact therewith for the purpose of expelling the compressed air and a portion of the liquid through the registering bucket ports and casing outlet port. The mixed compressed air and excess liquid are carried to a separator from whence the air is withdrawn for use or storage and the liquid is again pumped into the compressor as before. 70

Other objects and features of novelty will be apparent from the following specification when read in connection with the accompanying drawings, in which exemplary embodiments of the invention are illustrated. 75

Figure 1 is a diagrammatic view of one form of apparatus embodying the principles of the invention;

Figure 2 is a transverse vertical cross section of the air compressor shown in Figure 1 80 taken on the line 2—2;

Figure 3 is a horizontal cross section taken on the line 3—3 of Fig. 2;

Figure 4 is a vertical sectional view taken on the line 4—4 of Fig. 3;

Figure 5 is a fragmentary diagonal cross section taken on the line 5—5 of Fig. 2;

Figure 6 is a diagonal cross section of another embodiment of the invention taken on a line corresponding to line 5—5 of Fig. 2; and 90

Figure 7 is a view similar to Fig. 2 showing a further modified form of the invention.

Referring more particularly to the drawings, the apparatus as disclosed in Fig. 1, 100

comprises an air compressor designated generally by the letter A, a water pump designated B and a water and air separator to which is applied the letter C.

The air compressor is shown in detail in Figs. 2 to 5 inclusive, and comprises a housing 5, the base of which constitutes the support for the compressor. A rotor 6 is mounted within the housing, and is secured as by keys 7 to the shaft 8, which is journaled in the bearings 9 for rotation in the direction of the arrow shown in Fig. 2. The rotor 6 comprises a hub 19 carrying a series of substantially radial blades or vanes 11, slightly curved in the direction of rotation and connected by shrouds 12 and 13, which form with the vanes a series of buckets 17. In the shroud 13 between adjacent vanes and just outside the hub 10 are formed ports 18, one for each of the buckets 17.

An inner casing 19 is formed within the housing 5 and encloses rotor 6 at one side thereof and around its periphery, as clearly shown in Fig. 3. The outer wall of the casing 19 is approximately circular at the diametrically opposite portions 20 and 21 and approaches the periphery of the rotor at 21 close enough to prevent the passage of any of the water between the casing wall and the outer ends of the vanes 11. The casing wall is spaced from the ends of the vanes at 20 to provide a clearance for the passage of the compressed air as well as the body of water comprising the liquid piston. The lobe portions 22 and 23, however, are extended outwardly leaving substantially crescent shaped spaces between the rotor and outer casing wall at these points. A part of the outer wall of casing 19 between the portions 20 and 23 is cut away to provide an opening 25 communicating with an annular space 24 between the lobe casing 19 and the housing 5.

The housing 5 is provided with a chamber 26, as shown in Fig. 3, for the pressure water supply. This chamber is provided with an inlet 27 which is connected by a conduit 28 with the delivery pipe 29 of the water pump. Openings 30 afford communication from the water supply chamber 26 to the annular space 24.

On the other side of the housing 5 are provided semi-circular chambers 31 and 32, which are separated by the partition wall 33. The chamber 31 is formed with an inlet passage 34, to which the supply pipe 35 is connected. An elongated inlet opening 36 is provided in the inner wall of the chamber 31 at such a point as to be continually in communication with several of the bucket ports 18 as they rotate past said opening. A similar opening 37 slightly longer than opening 36 is formed in the inner wall of the chamber 32 to provide an outlet for the casing 19. This outlet opening 37 is similarly continually in communication with several of the

bucket ports 18 as they pass this opening near the end of their cycle of rotation from the inlet port 36. A discharge passage 38 leads from the chamber 32 and is connected as at 39 with the discharge conduit 40 through 70 which the water and compressed air flow to the separator C. The separator may be of any preferred type, and is provided with a discharge pipe 41 for the separated compressed air and a return pipe 42 is connected to the 75 pump B so that a portion of the separated water may be recirculated to furnish the supply of pressure water for the compressor.

In operation the casing 19 is initially partly filled with make-up water, and the 80 slight additional amount necessary for replacing any losses or for cooling purposes is introduced into the air supply pipe 35 by means of the pipe 48. It is obvious that, together with the high pressure water introduced to the compressor through the inlet 27, this make-up and cooling water will furnish an excess of water in the separator C over that needed for recirculation as pressure water, so an outlet 49 is provided in the 85 separator which may be controlled by a ball float valve or other suitable means.

When the rotor 6 is driven by the shaft 8 in the direction of the arrow, as shown in Fig. 2, the body of make-up water assumes a ring shape and revolves within the casing 19, and due to the centrifugal force and the shape of the outer wall of the casing 19 portions of the revolving ring of water will alternately approach and recede from the center or hub of the rotor 6. When any one of the buckets 17 has just passed the outlet opening 37, it will be substantially filled with water due to the air having just been ejected therefrom and the revolving body of make-up water being at this point directed toward the center of the casing by the approach of the casing wall toward the peripheries of the rotor at 21.

As the ring of water constituting the liquid piston begins to recede centrifugally from the bucket 17 upon reaching the lobe 22, air is drawn into the buckets through the inlet port 36 of the casing and the bucket ports 18. Then when the ports 18 pass beyond the port 36 and after the point of maximum capacity of lobe 22 is reached, the casing wall begins to converge toward the rotor again causing the adjacent portion of the annular body of water to again 110 approach the center of the rotor compressing the air in the buckets 17. This compression due to the revolving liquid piston comprising the body of make-up water attains its maximum as the rotor buckets 17 115 pass the point 20 of the casing wall.

When the buckets reach the opening 25 which affords communication between the casing 19 and the annular space 24, the high pressure water in this annular space 120

24 exerts a further compressive force on the entrapped compressed air in the bucket. The speed at which the rotor is driven is regulated with respect to the pressure of the 5 water in the space 24 so that the velocity energy of the water in the bucket is great enough to prevent the passage in the space 24 from causing a back-flow between the portion 20 of the lobe casing wall and the 10 rotor vanes, even if a slightly greater clearance were provided between the periphery of the rotor and the portion 20 of the casing wall.

When the bucket reaches a point opposite 15 the edge of the lobe portion 23 of the casing wall its port 18 is in communication with the outlet opening 37 and, due to the converging shape of this portion of the casing wall, the compressed air and part of the water contained in the bucket is forced through the outlet opening 37 into the outlet chamber 32 and thence through the discharge passage 38 and pipe 40 into the separator C. Here the 20 water is removed from the water and air mixture and returns through the pipe 42 to the pump B for recirculation. The separated 25 compressed air passes out through the pipe 41 and is available to supply the various demands to which it may be subjected.

30 In the form of the invention shown in Fig. 6, the water pump is contained within the same casing as the air pump. An impeller 43, such as is commonly used in centrifugal water pumps, is secured to the shaft 8 as by 35 keys 44 in such a manner as to rotate with the shaft in the space between the housing 5 and the casing 19.

In the operation of this form of the invention, water at ordinary low pressure may be 40 supplied at the intake 27 so as to fill the chamber 26. The impeller pumps the water from the chamber 26 into the space 24 around the casing 19, and maintains a steady pressure, which is applied to the air being compressed 45 in the rotor 6 in exactly the same manner as shown in Figure 2. In this case, of course, the pump B and its connection may be dispensed with.

Figure 7 shows a modified form of lobe 50 casing which may be used with either of the previously described installations, that is, irrespective of whether the water pump is located within the same housing as the air compressing rotor, or constitutes a separate unit 55 which pumps the water from some distance into the housing. In this form of the invention there is inserted in the cut away portion of the casing wall, corresponding to the opening 25 in Figure 2, the converging wall section 47. This arrangement provides, instead of the single opening 25 as in the previously described embodiment, two openings 45 and 46 through which the high pressure water from the annular space 24 may be supplied to 60 the rotor buckets. The converging outer wall

section 47 is so disposed that the air is subjected to a further compressive force after the admission of high pressure water through the opening 46 and before the bucket port 18 reaches the outlet opening 37. When the bucket is adjacent to the outlet opening 37 its contents are again subjected to the high pressure water through opening 45 and the compressed air is finally ejected by the aid of the converging wall 23.

75 Although the apparatus forming the subject of this invention has been specifically described and illustrated as being used to compress air by the use of water as the compressing medium, it is to be understood that the device may be used to compress any gas or compressible fluid, and that oil or any other liquid may be used as the compressing medium. Furthermore, the invention is not limited to the specific embodiments described and 80 illustrated but includes all modifications and changes which may come within the scope of the appended claims.

85 Having thus described the invention what is claimed as new and desired to be secured by Letters Patent is:

90 1. The method of compressing air which consists in passing the air into a fluid displacement compressor of the rotary liquid ring type, effecting an initial compression of 95 the air therein, introducing additional liquid into the compressor at high pressure at a plurality of successive points and subjecting said air to the action of said high pressure liquid whereby further compression of the air is 100 effected.

105 2. The combination with a fluid displacement air pump of the rotary liquid ring type having a lobed casing and a rotor therein, a chamber adjacent said casing, means for supplying liquid under pressure to said chamber, a portion of the outer peripheral wall of said lobed casing being cut away affording an entrance for said liquid from said chamber to said casing, whereby increased pressure 110 may be applied to the air therein by said liquid under pressure.

115 3. In an air compressor, a casing with a rotor therein adapted to apply an initial compression to the air in said casing, and a housing enveloping said casing and containing liquid under pressure, portions of the wall of said casing being cut away at a plurality of successive points to admit said liquid under pressure from said housing to the casing, whereby the air therein may be subjected to the added pressure of said liquid.

120 4. The combination with a rotary air pump having a casing with a rotor therein, whereby the air is given an initial compression, and a housing enveloping said casing, a liquid pump within said housing for supplying liquid under pressure to said casing, a portion of the wall of said casing being cut away affording communication between said casing 125 130

and said liquid pump, whereby increased pressure may be applied to the air in the casing by said liquid under pressure.

5. The combination with a rotary air pump having a casing with a rotor therein, whereby the air is given an initial compression, and a housing enveloping said casing, a liquid pump co-axial with said rotor shaft within said housing for supplying liquid under pressure to said casing, a portion of the wall of said casing being cut away affording communication between said casing and said liquid pump, whereby increased pressure may be applied to the air in the casing by said liquid under pressure.

6. Apparatus of the character described comprising in combination, a fluid displacement air compressor of the type employing a rotary liquid ring, said compressor being provided with a lobed casing, a liquid pump in communication with said casing for supplying liquid under pressure thereto, whereby the pressure of the liquid is added to the air compressed by said air compressor.

7. Apparatus of the character described comprising in combination, a rotary liquid ring air compressor having a casing, a pump in communication with said casing for supplying liquid under pressure thereto, whereby the added pressure of the liquid is transmitted to the air already under compression by said liquid in said rotary air compressor, and a liquid and air separator connected to the discharge of the compressor and the intake of the pump, whereby the liquid for producing the high pressure may be separated and recirculated.

8. Apparatus of the character described comprising in combination, an air compressor having a lobed casing, a rotor therein, a housing enveloping said lobed casing, and a liquid pump within the housing, said lobed casing having a portion of its wall cut away, whereby the pressure developed by said liquid pump may act on the air being compressed by the rotor.

9. Apparatus of the character described, comprising in combination, an air compressor of the rotary liquid piston type having a casing, a shaft journaled for rotation therein, and a rotor keyed to said shaft, a housing enveloping said casing, and a centrifugal liquid pump within said housing having an impeller keyed to the shaft of said rotor, said casing having a portion of its wall cut away whereby the pressure developed by said liquid impeller may act upon the air being compressed by said air compressor.

10. In an air compressor, in combination, a housing, a casing within said housing adapted to contain a liquid, a rotor within said casing provided with shrouds and vanes which form an annular series of buckets within said rotor, lobes formed at spaced intervals around said casing, the arrangement

of said parts being such that rotation of said rotor generates a revolving liquid annulus which is adapted to effect compression of air drawn into said buckets, a chamber between said housing and said casing adapted to be supplied with liquid under high pressure, a portion of said casing wall being removed to provide communication between said chamber and the interior of said casing, whereby the pressure of the high pressure liquid may be transmitted to the air compressed by the action of said liquid annulus.

11. In an air compressor, in combination, a housing, a casing within said housing provided with air inlet and outlet ports and adapted to be partly filled with a liquid, a chamber formed between said housing and said casing and adapted to be supplied with high pressure liquid, a rotor within said casing provided with buckets, ports in the walls of said buckets, lobes formed at spaced intervals around the circumference of said casing, the arrangement of said parts being such that rotation of said rotor generates a revolving liquid annulus which together with the walls of said buckets forms chambers which are adapted to expand as they pass a diverging portion of a lobe and contract as they pass a converging portion of a lobe, said air inlet port of said casing being adapted to register with the ports of said buckets as they pass the diverging portion of a lobe and the outlet port being adapted to register with the bucket ports as they pass the converging portion of the next succeeding lobe, the diverging portion of said last named lobe being cut away to provide communication between said high pressure liquid chamber and said casing, whereby the pressure of said liquid may be transmitted to the air compressed by the action of said liquid annulus.

12. In an air compressor, in combination means including a rotary liquid ring piston for compressing air therein, and means for admitting high pressure liquid to said compressor at a plurality of successive points during the compression of said air.

13. Apparatus of the character described, comprising, in combination, an air pump or a compressor of the rotary liquid ring type, said pump or compressor being provided with a double lobed casing, a rotor adapted to operate in said casing, one of the lobes of said casing being provided with an air inlet port, a liquid ring generated by the movement of said rotor and adapted during the operation of the device to effect the initial compression of the air within said lobe, means for introducing liquid under pressure to the other of said lobes to increase the pressure of said air, and an outlet port in said second named lobe.

14. Apparatus of the character described comprising, in combination, an air pump or a compressor of the rotary liquid ring type,

said pump or compressor being provided with a double lobed casing, a rotor adapted to operate in said casing, one of the lobes of said casing being provided with an air inlet port, a liquid ring generated by the movement of said rotor and adapted during the operation of the device to effect the initial compression of the air within said lobe, a portion of the outer peripheral wall of the other lobe being cut away to admit additional water under pressure to said casing to effect a further compression of the air, and an outlet port in said second named lobe.

15. The combination set forth in claim 14 in which a wall section is inserted in the space provided by said cut-away portion of the wall of said second named lobe and is spaced from the edges of the remaining wall portions so as to provide a plurality of inlet 20 openings for said liquid under pressure, said wall section converging toward the periphery of said rotor in the direction of rotation thereof.

16. In an apparatus of the class described, an air compressor of the rotary liquid ring type, comprising, a rotor, a rotor casing, a lobe formed in said casing whereby the liquid ring generated by the movement of said rotor is caused to effect an initial compression 30 of the air in said casing, all of the liquid forming said ring remaining in said lobe during the compression of the air therein, a source of liquid under pressure, means for introducing said last named liquid into said 35 casing at a point beyond said lobe, and means for exhausting said air and a portion of both of said quantities of liquid from said casing.

17. In an apparatus of the class described, an air compressor of the rotary liquid ring type, comprising a rotor, a rotor casing, a lobe formed in said casing, whereby the liquid ring generated by the movement of said rotor is caused to effect an initial compression 45 of the air in said casing, all of the liquid forming said ring remaining in said lobe during the compression of the air therein, a pump for applying liquid under pressure, means for introducing said last named liquid into said casing at a point beyond said lobe, a port for exhausting said air and a portion 50 of both of said quantities of liquid from said casing, and a liquid and air separator connected to said exhaust port and the intake of said pump, whereby the liquid for producing the added pressure may be separated and recirculated.

In testimony whereof I hereunto affix my signature.

HAROLD L. NASH.
